UNITED STATES PATENT OFFICE.

CHARLES H. PETERS, OF CINCINNATI, OHIO.

COMBINATION OF CHAMBER-LAMP AND LANTERN.

Specification forming part of Letters Patent No. 38,500, dated May 12, 1863.

To all whom it may concern:

Be it known that I, CHARLES H. PETERS, of Cincinnati, Hamilton county, Ohio, have invented a new and useful Convertible Chamber-Lamp and Lantern; and I do hereby declare the following to be a full, clear, and exact description thereof, reference being had to the annexed drawings, making part of this specification.

This improvement consists in, first, the provision of a handled or chamber lamp adapted for customary use about the house, and for occasional attachment to a glazed screen or shell, so as to combine the advantages of a lantern and of a convenient hand-lamp; second, a provision for the double purpose of equalizing the in-draft and securing the panes.

Figure 1 is a perspective view of the lamp and shell detached. Fig. 2 is an axial section of the shell.

A is a complete chamber or hand lamp, having the customary ring or handle B.

C C' C'' are three studs or projections from the neck or upper portion of the lamp-reservoir, adapted to enter gates D in the bottom E of the glazed shell or lantern-case F, and be secured by a partial rotation of the lamp. The handle B and reservoir A, being at all times external with respect to the shell F, never become overheated, so as to interfere with the uniformity of combustion or the use of the lamp proper for indoor purposes upon the withdrawal of case. The lower edges of the panes G are secured by guards H, which are formed by being punched up from the tin bottom E of the casing, so as to leave apertures I for the in-draft, to which the guards H act as deflectors to disperse the draft and

to prevent any sudden gust coming in contact with the flame. The guards H are thus made to serve two uses. The lantern-chimney is traversed at its lower part by a perforated dome or arched diaphragm, J, and near its upper part by an annular ascending flange or diaphragm, K.

L are apertures placed equidistant around the chimney-sides between the dome J and the flange K.

M is a conical cowl, whose scalloped sides form a series of upper openings, N, just above the flange K.

The above-described series of diaphragms, apertures, &c., acts to effectually check and disseminate any sudden gusts which may blow into the top of the lantern, while the in-draft apertures I perform a similar service for the lower part.

I claim herein as new and of my invention—

1. The chamber or handled house-lamp A B, provided with studs C C' C'', projecting from the upper portion of the reservoir and adapted to interlock within the gated bottom of a lantern-case, F, the whole being constructed and adapted for the separate uses of a lantern and a house-lamp, as set forth.

2. The described arrangement of the guards H and apertures I, for the double purpose of retaining the panes and of deflecting the in-draft, substantially as set forth.

In testimony of which invention I hereunto set my hand.

CHARLES H. PETERS.
